DESIGN FOR A LAMP

William H. Chamberlain, New York, N. Y., assignor to Solex Lights Corporation, New York, N. Y., a corporation of New York

Application June 26, 1934, Serial No. 52,343

Term of patent 3½ years

To all whom it may concern:

Be it known that I, William H. Chamberlain, a citizen of the United States, residing in the city of New York, county of New York, and State of New York, have invented a new, original, and ornamental Design for a Lamp, of which the following is a specification, reference being had to the accompanying drawing, forming a part thereof.

Fig. 1 is an elevation of a lamp embodying the

design of this invention for use in churches and elsewhere, the light bulb containing a glowing crucifix extending above the ornamental holder illustrated.

Fig. 2 is a top plan view of the device shown in Fig. 1.

I claim:

The ornamental design for a lamp, substantially as shown and described.

WILLIAM H. CHAMBERLAIN.
